Primary Examiner — Messina L Smith*Assistant Examiner* — Elizabeth Borsetti(74) *Attorney, Agent, or Firm* — Jeenam Park(57) **CLAIM**

The ornamental design for a hair dryer, as shown and described.

DESCRIPTION

FIG. 1 is a front, right and top perspective view of a hair dryer, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view of the hair dryer;

FIG. 8 is an enlarged bottom plan view of the hair dryer; and, FIG. 9 is an enlarged view of a portion of the hair dryer shown within the area designated as 9 in FIG. 2.

The broken lines shown in the drawings illustrate portions of the hair dryer that form no part of the claimed design. The dot-dash broken lines surrounding portions of the hair dryer in FIG. 2 and illustrated in the enlarged view in FIG. 9 form no part of the claimed design.
